TABLE

Ernest L. Swarts and Orville B. Solie, Rockford, Ill.,
assignors to The Lane Company, Inc., Altavista, Va.,
a corporation of Virginia

Filed Nov. 2, 1959, Ser. No. 58,149

Term of patent 14 years

(Cl. D33—14)

Fig. 1.

Fig. 2.

The essential features of the design are shown in solid lines in the drawings.

We claim:

The ornamental design for a table, as shown and described.
